SYNTHESIS OF COMPOUNDS OF THE
ASCORBIC ACID SERIESWilhelm Wenner, Montclair, N. J., assignor to
Hoffmann-La Roche Inc., a corporation of New
JerseyNo Drawing. Application October 27, 1945,
Serial No. 625,109

20 Claims. (Cl. 260—344.5)

1

My invention relates to the synthesis of ascorbic acids. Acids of this class possess utility, e. g., as antiscorbutic agents and as antioxidants.

My invention particularly relates to the production of ascorbic acids from alkyl esters of the corresponding keto-acids, according to the general formulation:

in which *n* represents zero (0) or a low integer, "alkyl" represents methyl, ethyl, or the like, and 20 R stands for H or OH.

The formulae I and II are generic in their characterization, no specific stereochemical configuration being designated. The general conversion is represented above with a broken line below the No. 4 carbon atom, since the synthesis of this application is particularly associated with the lactonization brought about in that part of the ester (I) above the broken line. It will be apparent, therefore, that, since *n* may be zero or an integer, esters of keto-pentonic acids, esters of keto-hexonic acids, and esters of keto-heptonic acids, may be subjected to my novel transformation.

It is of particular significance that my novel conversion may be employed not only for the treatment of isolated esters, but also for the transformation of esters as they are present in the reaction mixtures in which they are made.

Typical and important examples of keto-acids which may be esterified and treated by my novel process are 2-keto-d-gluconic acid (III) and 2-keto-l-gulonic acid (IV).

Esters of 2-keto-d-gluconic acid (III), e. g., methyl ester or ethyl ester, yield d-isoascorbic acid compounds (V), also known as d-arabo

ascorbic acid, whereas esters of 2-keto-gulonic acid (IV), produce l-ascorbic acid (VI), also known as vitamin C.

The formulae d-isoascorbic acid and l-ascorbic acid are reproduced, respectively, as (V) and (VI).

2-keto-6-desoxy-l-gulonic acid ester (VII) is converted into the physiologically active 6-desoxy-l-ascorbic acid (VIII), as represented by:

30 The general process of lactonization to convert, e. g., 2-keto-l-gulonic acid into ascorbic acid, is known in the art. Such lactonization has been carried out by heating the free acid in neutral, acid, or alkaline solution or by heating esters of 35 the keto-acid with sodium alkoxides, sodium acetate, calcium carbonate, or the like. Maurer (Ber. 1941, 74, 1003, 1006) has reported a conversion (determined by titration only) by the use of water - miscible diethyl - amine. Tertiary 40 amines have also been employed as conversion agents (U. S. P. No. 2,160,621).

I have found that certain secondary amines are of particular value for effecting the lactonization of alkyl esters of the keto-acids described 45 above. These secondary amines are characterized by relatively strong basicity and relatively low solubility in water. Specific examples of suitable secondary amines are dicyclohexylamine, N-methyl-cyclohexylamine, N-ethyl - cyclohexyl-50 amine, N-propyl - cyclohexylamine, and N-methyl-benzylamine. Other strongly basic, relatively water-insoluble secondary amines can also be employed.

At least one molecular equivalent of the amine 55 must be employed for each mole of the ester.

The temperature is preferably maintained at about 60°-70° C.

It may be pointed out that in the course of the lactonization of the keto-acid esters, the amine used for the conversion forms a salt of the resulting lactonized acid, e. g., of d-isoascorbic acid or of l-ascorbic acid. Thus the treatment of methyl-2-keto-d-gluconate with dicyclohexylamine, produces dicyclohexylamine-d-isoascorbate. By treatment of the amine salt with an alkaline agent, e. g., sodium hydroxide, sodium-d-isoascorbate is formed. The conversion into the free acid, e. g., d-isoascorbic acid, is carried out by acidification with, e. g., hydrochloric acid.

It will be apparent, therefore, that the general course of reaction, may be represented as follows:

The significance of the invention will be made apparent by the following illustrative examples, which will serve as a guide for those skilled in the art to carry out the transformation. It will be apparent from these examples that the esters may be treated in isolated condition, or in the non-isolated form. The latter modification is of particular value from a commercial viewpoint.

It will be appreciated that the proportions of reactants, times of reaction, temperatures of reaction, and the like, may be varied; and that supplementary processes, such as purification and the like, may be resorted to wherever found desirable or convenient. These and other variations and modifications will be evident to those skilled in the art in the light of the guiding principles disclosed herein.

Example 1

104 parts of 2-keto-l-gulonic acid methylester, 800 parts of absolute alcohol, and 91 parts of dicyclohexylamine are stirred and heated for 1 to 1½ hours in a waterbath kept at 70°. After this time a sample titrated with iodine solution after acidification shows a rate of conversion of 90-100%. The mixture is cooled to room-temperature. A solution of 21 parts of sodium hydroxide in 220 parts of 95% alcohol is added slowly. Sodium l-ascorbate precipitates in small crystals. It is filtered, washed with 350 parts of alcohol and dried at room-temperature in a vacuum drier. This sodium salt is converted into the free l-ascorbic acid by known methods, e. g., by stirring the crude salt in alcohol and adding the calculated amount of alcoholic hydrochloric acid, filtering the solution from the sodium chloride, and evaporating the filtrate.

Example 2

104 parts of 98% sulfuric acid is mixed with 3000 parts of anhydrous alcohol. 472 parts of technical calcium 2-keto-d-gluconate are added. The agitated mixture is heated under strong reflux for 4 hours. Heating is then discontinued, and the mixture stirred over night. 433 parts of dicyclohexylamine are added and the mixture is heated to 58 to 60° with stirring. Samples are withdrawn in intervals and, after dilution with water and acidification, are titrated. When no more increase in iodine titration is noted, the solution is cooled. It is filtered from the calcium sulfate. The latter is washed with alcohol and with water. The main filtrate and the washes are combined. With stirring, a solution

of 80 parts of sodium hydroxide in 210 parts of water is added slowly. Sodium d-isoascorbate precipitates. The mixture is cooled and stirred overnight. The sodium d-isoascorbate is filtered and washed with absolute alcohol. It is dried at a temperature not exceeding 30° in a vacuum oven. It can be converted to the free acid by the method shown in Example 1.

Example 3

10 146 parts of diacetone-2-keto-l-gulonic acid are refluxed with 1200 parts of methanol and 22 parts of 18% conc. hydrochloric acid for 10 hours. After cooling 1200 parts of benzene are 15 added. The mixture is concentrated to a volume of about 200 cc. To this solution are added 600 parts of methanol and 95 parts of dicyclohexylamine. The mixture is stirred and heated for 2 hours to 60-65°. After cooling a solution of 21 parts of sodium hydroxide in 200 parts of 95% methanol is slowly added. Sodium l-ascorbate 20 separates. It is filtered after cooling overnight and dried at a temperature not exceeding 30° in a vacuum.

Example 4

25 20.8 grams of methyl-2-keto-d-gluconate are suspended in 108 cc. of absolute ethanol. To this mixture is added 18.1 grams of dicyclohexylamine. The mixture is stirred and heated to 70°. In about 10 minutes the ester is dissolved. The conversion is followed by titration. Samples of 2 cc. are diluted with water and acidified, and then titrated with 0.1 n-iodine solution. The 30 conversion is finished after about 1½ hours. After cooling, 20 cc. of water are added. The mixture is cooled and a solution of 4.4 grams of sodium hydroxide in 20 cc. of water is slowly 35 added with stirring. Sodium d-isoascorbate precipitates. It is filtered, washed with some ice cold 90% ethanol, and dried.

Example 5

40 58 grams of diacetone-2-keto-l-gulonic acid, 45 340 cc. of absolute ethanol, and 4 cc. of aqueous concentrated hydrochloric acid are refluxed for eight hours. To the cooled solution are added 45 grams of dicyclohexylamine. The mixture is stirred and heated to 60-70° for 2 hours. After 50 cooling, a solution of 10 grams sodium hydroxide in 125 cc. of 95% ethanol is slowly added with stirring. Sodium l-ascorbate crystallizes and is isolated by filtration.

Example 6

55 20.8 grams methyl-2-keto-gulonate, 170 cc. 55 absolute ethanol, and 13 grams of N-ethyl-cyclohexylamine are stirred for 1½ hours at 70°. After cooling, 4.2 grams sodium hydroxide dissolved in 55 cc. of 95% ethanol are added slowly. Sodium-l-ascorbate crystallizes and is isolated by filtration.

Example 7

60 65 20.8 grams of methyl-2-keto-gluconate, 170 cc. absolute ethanol, and 13 grams of N-ethyl-cyclohexylamine are heated with stirring to 68-70° for one and one half hours. To the cooled solution 70 20 cc. of water are added. To the mixture a solution of 4.2 grams sodium hydroxide dissolved in 20 cc. of water is added dropwise with stirring. Sodium d-isoascorbate separates as a heavy, sandy crystalline powder. It is filtered, washed with 200 cc. of absolute ethanol, and 75 dried.

Example 8

41.6 grams of methyl-2-ketogluconate, 340 cc. of absolute ethanol, and 25 grams of N-methylbenzylamine are heated with stirring to 65-70° for 1½ hours. To the cooled solution 40 cc. of water are added. To the mixture a solution of 8.4 grams sodium hydroxide dissolved in 40 cc. of water is added dropwise with stirring. Sodium-d-isoascorbate separates as a yellowish crystalline powder, which is filtered, washed with absolute ethanol, and dried.

Example 9

20.8 grams of methyl-2-ketogulonate, 160 cc. of absolute ethanol, and 12.4 grams of N-methylbenzylamine are heated for 1½ to 2 hours with stirring. To the cooled solution a solution of 4.2 grams of sodium hydroxide in 60 cc. of 95% ethanol is added slowly. Sodium-l-ascorbate precipitates and is filtered by suction.

I claim:

1. The process of synthesizing compounds of the ascorbic acid series, which comprises subjecting keto-acid esters of the general formula

in which n represents 0, 1 or 2, and R is a member selected from the group consisting of H and OH, to the action of at least a molecular equivalent of a secondary amine selected from the group consisting of dicyclohexylamine, N-methyl-cyclohexylamine, N-ethyl-cyclohexylamine, N-propyl-cyclohexylamine, and N-methyl-benzylamine.

2. The process of claim 1 in which the conversion is carried out at about 60°-70° C.

3. The process of claim 1 in which the amine is dicyclohexylamine.

4. The process of claim 1 in which the amine is N-ethyl-cyclohexylamine.

5. The process of claim 1 in which the ester is a methyl ester.

6. The process of claim 1 in which the ester is an ethyl ester.

7. The process of claim 1 in which the ester is methyl-2-keto-l-gulonate.

8. The process of claim 1 in which the ester is methyl-2-keto-d-gluconate.

9. The process of claim 1 in which the ester is 1-methyl-2-keto-l-gulonate, and the amine is dicyclohexylamine.

10. The process of claim 1 in which the ester is 1-methyl-2-keto-d-gluconate, and the amine is dicyclohexylamine.

11. The process of claim 1 which includes treating the resulting amine salt of the ascorbic acid with sodium hydroxide to form the corresponding sodium ascorbate.

12. The process of claim 1 which includes treating the resulting amine salt of the ascorbic acid with sodium hydroxide to form the corresponding sodium ascorbate, and converting said salt to the corresponding free ascorbic acid by means of an acid agent.

13. The process of claim 1 which includes treating the resulting amine salt of the ascorbic acid with sodium hydroxide to form the corresponding sodium ascorbate, followed by conversion of said salt to the corresponding free ascorbic acid by means of hydrochloric acid.

14. The process of claim 1 in which the reaction is carried out in the presence of an alcoholic medium.

15. The process of claim 1 in which the reaction is carried out in ethanol and the resulting amine salt of the ascorbic acid is treated with sodium hydroxide to form the corresponding sodium ascorbate.

16. The process of forming an isoascorbic acid compound which comprises subjecting methyl-2-keto-d-gluconate in an alcohol medium to dicyclohexylamine to form the corresponding amine salt of isoascorbic acid.

17. A process as in claim 16 in which the resulting amine salt is treated with sodium hydroxide to form the corresponding sodium isoascorbate.

18. The process of producing l-ascorbic acid compounds which comprises subjecting 2-keto-l-gulonic acid methylester to dicyclohexylamine in an alcohol medium to form the corresponding amine salt of l-ascorbic acid.

19. A process as in claim 18 in which the resulting amine salt is treated with sodium hydroxide to form the corresponding l-sodium ascorbate.

20. The process of claim 1, which includes treating the resulting amine salt of the ascorbic acid with an alkali metal alkaline agent to form the corresponding alkali metal ascorbate.
